Application February 26, 1957, Serial No. 642,423

2 Claims. (Cl. 340—324)

This invention relates to electric selective signalling systems, and has in view the provision of improved electrically-operated changing display indicators of the type arranged to display information (for example figures or letters or numbers or words) signified by code signals. The invention is an improvement in or modification of that which forms the subject of my issued U. S. Patent No. 2,723,391, November 8, 1955.

In the said prior specification, there is described and claimed an electrically-operated changing display indicator, of the kind in which a driven member has a normal position and a plurality of stopping positions at which different display surfaces are displayed, wherein a code switching device driven by the driven member provides in effect a controlling switch in each code branch of a control circuit which controls the setting of the driven member from the normal position to any particular stopping position as signified by a code signal, and comprises a rotor and fixed wipers arranged to make electrical contact with conducting code discs of this rotor, there being a control circuit code branch individual to each element of the code employed and a conducting code disc for each control circuit code branch, and each conducting code disc having portions cut away so that a through circuit between this disc and the associated fixed wiper exists only when the rotor is occupying certain positions, and the conducting discs being in permanent electrical connection with one another. As regards each particular control circuit code branch, the code switching device operates to cause the branch to be open whilst the driven member is at one or more stopping positions and to be closed whilst the driven member is at the remaining stopping position or positions. Also as regards each particular control circuit code branch, when it is required to set the driven member from a normal position to a stopping position signified by a code signal the branch is not connected to render it effective, subject to the switching performed by the code switching device, unless the signal element to which the branch pertains is, in the case of the particular code signal concerned, of a particular character (for example is a "mark" as opposed to a "space"). During the setting of the driven member from a normal position to a stopping position signified by a code signal, at any stopping position reached before the requisite stopping position is reached the condition obtains that one or more control circuit code branches are effective to cause the driving of the driven member to continue. At the requisite stopping position, the condition obtains that no control circuit code branch is effective to cause the driving of the driven member to continue, so that the driven member is stopped in this stopping position. For convenience in description, such an electrically-operated changing display indicator will hereinafter be referred to as an electrically-operated changing display indicator of the kind set forth.

In the particular form of electrically-operated changing display indicator of the kind set forth which is illus-

2

trated and described in detail in the prior specification referred to, the control circuit controls the driving of the driven member through the medium of a latch electromagnet having an armature which in its unoperated condition permits a latch to enter a notch in a notched wheel coupled to the driven member and bring the driven member to rest at a stopping position, and which in its operated condition both holds the latch out of engagement with the notches in the notched wheel and closes a latch electromagnet contact controlling the energisation of the electromagnet of an electromagnetic clutch which serves for coupling the driven member to a primary driving means common to a plurality of indicators.

According to the present invention, in an electrically-operated changing display indicator of the kind set forth the driving of the driven member is effected by a driving electromotor which is individual to the indicator, and which is permanently coupled to the driven member, and which is energised, when it is required to set the driven member from a normal position to a stopping position signified by a code signal, until the requisite stopping position is reached or is about to be reached, and friction which is normally operative to oppose movement of the driven member is relied upon to bring the driven member to rest in the requisite stopping position, the permanent coupling between the driving electromotor and the driven member being such that the electromotor drives the driven member through the medium of a high-ratio reduction gear train, so that variations, within the limits obtaining, in the number of revolutions due to momentum made by the rotor of the electromotor following upon the opening of the energising circuit of the electromotor have for practical purposes only a negligible effect upon the accuracy of the setting.

The individual driving electromotor may conveniently be an electromotor of the kind, arranged for operation from a direct current source, having an unwound rotor and field electromagnets which during the operation of the electromotor are connected in circuit sequentially by a commutator device. Electromotors of this kind are now well-known in connection with the so-called motor-driven uniselectors used in automatic telephone systems.

By way of example, two specific embodiments of the invention will now be described with reference to the accompanying drawings. Figs. 1 and 2 of the drawings are side and plan views respectively of the changing display indicator which forms one of these two embodiments. Fig. 3 shows the connections of the field electromagnets and commutator device of the kind of driving electromotor used in each of these two embodiments. Fig. 4 is a plan view of the changing display indicator which forms the other of these two embodiments. Fig. 5 is a side view of an end plate of the last mentioned indicator, this side view showing the end plate with the driving electromotor, gear train, and code switching device of the indicator in position thereon.

Referring firstly to Figs. 1 and 2, the changing display indicator to which these figures pertain is one in which twelve display slats 1 are carried by an endless chain 2 which is engaged by, and supported by, two sprocket wheels 3 and 4. The endless chain 2 is shown occupying its normal position in which the display surface of the particular display slat 5 is displayed, the front of the indicator being on the right as seen in the figures. The sprocket wheel 3 is mounted near the front end of the indicator, and is coupled, by a reduction gear comprising a pinion 6 and a gear wheel 7, to the rotor 8 of the code switching device of the indicator. This code switching device is, of course, a code switching device as previously referred to. The individual driving electromotor 9 of the indicator is mounted at the

opposite end of the indicator to the sprocket wheel 3, and is coupled to the sprocket wheel 4, which is mounted at an intermediate point along the length of the indicator, by a high-ratio reduction gear train. This reduction gear train comprises pinions 10 (Fig. 2), 12 and 14 and gear wheels 11, 13, and 15. The main mounting plate 16 of the indicator has secured to it five supporting members 17 by means of which the indicator as a whole is mounted in position in the situation in which it is to be used. The supporting members 17 are hexagonal in cross-section as seen looking at the plate 16, and each has in its end remote from the plate 16 a tapped hole for accommodating a fixing screw securing the indicator to a framework. Although Fig. 1 has been referred to as a side view, and Fig. 2 as a plan view, it must be clearly understood that the indicator is suitable for use in any position, and that it may for example be mounted with the plate 16 in a horizontal plane. The figures or letters or numbers or words or other representations on the display surfaces of the display slats 1 will of course be painted or otherwise formed thereon to suit the manner in which the indicator is mounted for use. For simplicity, the display surfaces that are seen in Fig. 2 have been left blank. Secured to the main mounting plate 16 by screws 18 are two subsidiary mounting plates 19 and 20. The subsidiary mounting plate 19 carries the sprocket wheel 3, the pinion 6, the gear wheel 7, and the rotor 8 of the code switching device. The subsidiary mounting plate 20 carries the gear wheels 11, 13 and 15, the pinions 12 and 14, and the sprocket wheel 4. The driving electromotor 9 is assembled, as regards the assembling together of its main constituent parts, on the main mounting plate 16 and subsidiary mounting plate 20.

The driving electromotor 9 is of the kind, previously referred to, arranged for operation from a direct current source and having an unwound rotor and field electromagnets which during the operation of the electromotor are connected in circuit sequentially by a commutator device. It has two field electromagnets 26a and 26b and a two-pole rotor 27 secured to spindle 21. Each field electromagnet consists of a winding on a central core, the core ends being formed as pole pieces for the rotor 27. Each field electromagnet has a pair of terminal tags 46 and has a soft-iron heel piece 22 by means of which it is secured to the mounting plates 16 and 20. The two field electromagnets are displayed so that their axes lie in a plane parallel to the mounting plates and at right angles to each other, and so that these axes when extended intersect on the axis of the spindle 21. Secured to the mounting plate 20 by means of two bolts 28 and corresponding supporting members 23 is a member 29 which supports a bracket 30. The mounting plate 20 and the supporting members 23 are of soft iron and are included in the magnetic circuit, a soft-iron yoke member 41 acting as a common return pole being secured to the members 23. The member 29 and bracket 30 have portions cut away to clear the spindle 21. The bracket 30 is secured to the member 29 by means of a bolt 34. The bracket 30 has a part 35 bent at right angles to the part which lies against the member 29. The part 35 supports a springset 36 comprising four cantilever type contact springs 42, 43, 44 and 45. The contact springs 42 and 43 constitute one pair of co-operating contact springs and the contact springs 44 and 45 constitute another pair, the two pairs on opposite sides of the spindle 21 as is clearly shown in Fig. 1. The outer spring of each pair has a side extension 38 at its unclamped end, the side extension on the spring 45 projecting towards the viewer when this particular outer spring is viewed as it is seen in Fig. 1, and the side extension on the spring 42 projecting in the opposite direction and therefore not being seen in Fig. 1. The side extension on the spring 45 is adapted to be operated on by a two-nosed cam 39b (one whole side of which is seen in Fig. 1), and the side extension on the spring 42 is adapted to be operated on

by a two-nosed cam 39a (one side of each nose of which is seen in Fig. 1), the two cams being mounted a small distance apart on the spindle 21 and moving with the rotor 27. As will be seen from Fig. 1, the two noses of each cam are diametrically opposite, and the noses on one cam are staggered by 90 degrees with respect to those on the other cam. Cam 39a operates to separate the two springs 42 and 43 by the bearing of either of its noses against the side extension on the spring 42, and cam 39b operates correspondingly to separate the two springs 44 and 45. The springset 36 provides permanent connection between the two inner springs 43 and 44 within the springset, and has a single terminal tag for these two springs. It has individual terminal tags for the two outer springs 42 and 45. The four springs carry noble metal contacts at their free ends.

Referring now to Fig. 3 as well as to Figs. 1 and 2, the two field electromagnets of the driving electromotor 9 are connected so that the magnetic polarity of the pole piece of electromagnet 26a resulting from the energisation of the electromagnet 26a is the same as the magnetic polarity of the pole piece of electromagnet 26b resulting from the energisation of electromagnet 26b. The electromotor drives when, and for as long as, its supply leads 24 and 25 (Fig. 3) are connected in circuit across a suitable direct current source. When the indicator now being described is connected in circuit ready for use, the lead 24 is connected to the negative pole of the direct current source concerned, and the lead 25 is connected to wiper 53 of the code switching device of the indicator. When a requirement for the driving of the electromotor arises, whether for setting the endless chain 2 from its normal position to a stopping position signified by a code signal or for resetting this chain to its normal position, a circuit connecting the lead 25 to the positive pole of the direct current source concerned is completed over the code switching device and is maintained until the endless chain has been driven to the requisite position whereupon the circuit is opened to bring the chain to rest. The arrangement of the code switching device to this end will be referred to in more detail shortly. Assuming by way of example that the rotor 27 of the electromotor occupies the position in which it is shown in Fig. 1 at the time lead 25 becomes connected through to the positive pole of the direct current source then at this time cam 39b is holding contact spring 45 out of contact with contact spring 44, and contact springs 42 and 43 are in contact with each other. Accordingly, field electromagnet 26a is energised, with the result that the rotor 27 is pulled round in the clockwise direction as seen in Fig. 1. As the rotor 27 moves through a quarter of a revolution, cam 39b allows contact spring 45 to move into contact with contact spring 44 and close an energising circuit for field electromagnet 26b, and then cam 39a pushes contact spring 42 out of engagement with spring 43 with the result that field electromagnet 26a is de-energised. Consequently the rotor 27 is pulled round further in the same direction to complete a further quarter of a revolution, and so on as long as lead 25 remains connected through to the positive pole of the direct current source.

The rotor 8 of the code switching device of the indicator now being described includes six conducting discs 47, 48, 49, 50, 51, and 52 which are in permanent electrical connection with one another through the medium of five conducting spacers 59. The six conducting discs and the five conducting spacers are suitably clamped together and insulated from the mounting plates 19 and 16. Disc 47 is a feeder disc, disc 48 is a reset disc, and discs 49, 50, 51, and 52 are code discs. The reduction gear by which the sprocket wheel 3 is coupled to the rotor 8 is arranged to have a ratio such that movement of the sprocket wheel 3 corresponding to movement of the endless chain 2 from one stopping position to the next succeeding stopping position produce one twelfth of

a revolution of the rotor 8. Fixed wipers 53, 54, 55, 56, 57, and 58 are associated with the conducting discs 47, 48, 49, 50, 51, and 52 respectively. Each wiper is of the split type comprising two parts arranged to engage the two surfaces of the associated conducting disc. The wiper assembly is secured to the main mounting plate 16, the fixed wipers being suitably insulated from one another and from the mounting plate. The wipers have terminal tags 60. Movement of the endless chain 2, whether for setting the chain to cause a particular display surface to be displayed or for resetting the chain to its normal position is always in the direction which brings about clockwise movement, as seen in Fig. 1, of the rotor 8.

For the purposes of this description it will be assumed that the display surface which is displayed when the endless chain 2 is occupying its normal position is a blank, and the display surfaces which are displayed when the endless chain is at its first, second, third, fourth, fifth, sixth, seventh, eighth, ninth, tenth, and eleventh stopping positions from normal will be termed display surfaces No. 1, No. 2, No. 3, No. 4, No. 5, No. 6, No. 7, No. 8, No. 9, No. 10, and No. 11 respectively. It will be clear from what has already been said that one complete movement of the endless chain 2 from its normal position through the different display positions and back to its normal position produces one revolution of the rotor 8 of the code switching device. To reset the endless chain to its normal position, the wiper 54 associated with the reset disc 48 is connected (in the external control circuit by which the indicator is being controlled) to the positive pole of the direct current source used for operating the driving electromotor 9, the wipers 55, 56, 57, and 58 being of course left disconnected from this pole so far as external connections to them are concerned. To set the endless chain to display the different display surfaces, different combinations of the wipers 55, 56, 57, and 58 associated with the code discs are connected (in the said external control circuit) to the positive pole of the said direct current source, the wiper 54 being of course left disconnected from this pole so far as the external connections to the wiper are concerned. The different combinations involved are as shown in the following table:

Display surface to be displayed	Corresponding stopping position from normal	Wipers connected externally to positive pole of direct current source
No. 1	first	55
No. 2	second	56
No. 3	third	55 56
No. 4	fourth	57
No. 5	fifth	55 57
No. 6	sixth	56 57
No. 7	seventh	55 56 57
No. 8	eighth	58
No. 9	ninth	55 58
No. 10	tenth	56 58
No. 11	eleventh	55 56 58

A code signal signifying that a particular display surface is to be displayed is a four-element binary code one, the first element determining whether wiper 55 is or is not connected externally to the positive pole of the direct current source, the second element determining whether wiper 56 is or is not so connected, the third element determining whether wiper 57 is or is not so connected, and the third element determining whether wiper 58 is or is not so connected. Each of the conducting discs 48, 49, 50, 51 and 52 has portions cut away, so that a through circuit between the disc and the associated fixed wiper only exists when the rotor 8 of the code switching device is occupying certain positions or moving between certain positions, i. e. when the endless chain 2 is occupying certain positions or moving between certain positions. The form of the reset disc 48 is such that no through circuit between the disc and its associated wiper

54 exists when the endless chain 2 is occupying its normal position, but that such a through circuit is closed during the course of movement of the chain from its normal position to its first stopping position (from normal) and thereafter remains closed until the chain again gets back to its normal position whereupon this through circuit is opened. The form of the code disc 49 is such that a through circuit between the disc and its associated wiper 55 exists when the endless chain 2 is occupying its normal position, and that during movement of the chain from its normal position through the different stopping positions this through circuit is opened when the chain reaches its first stopping position (from normal), is again closed during the course of the movement of the chain from its first to its second stopping position, is again opened when the chain reaches its third stopping position, is again closed during the course of the movement of the chain from its third to its fourth stopping position, is again opened when the chain reaches its fifth stopping position, and so on. The form of the code disc 50 is such that a through circuit between the disc and its associated wiper 56 exists when the endless chain 2 is occupying its normal position, and that during movement of the chain from its normal position through the different stopping positions this through circuit is opened when the chain reaches its second stopping position (from normal), is again closed during the course of the movement of the chain from its third to its fourth stopping position, is again opened when the chain reaches its sixth stopping position, is again closed during the course of the movement of the chain from its seventh to its eighth stopping position, is again opened when the chain reaches its tenth stopping position, and is again closed during the course of the movement of the chain from its eleventh stopping position to its normal position. The form of the code disc 51 is such that a through circuit between the disc and its associated wiper 57 exists when the endless chain 2 is occupying its normal position, and that during movement of the chain from its normal position through the different stopping positions this through circuit is opened when the chain reaches its fourth stopping position (from normal), and is again closed during the course of the movement of the chain from its eleventh stopping position to its normal position. The form of the code disc 52 is such that a through circuit between the disc and its associated wiper 58 exists when the endless chain 2 is occupying its normal position, and that during movement of the chain from its normal position through the different stopping positions this through circuit is opened when the chain reaches its eighth stopping position (from normal), and is again closed during the course of the movement of the chain from its eleventh stopping position to its normal position.

In considering the operation of the indicator now being referred to, it must be borne in mind that the conducting discs 47, 48, 49, 50, 51 and 52 are all in permanent electrical connection with one another through the medium of the five conducting spacers 59. The individual driving electromotor 9 of the indicator is in effect connected in a control circuit which has a code branch for each element of the code concerned. The code branch for the first element of the code includes code disc 49 and wiper 55, the code branch for the second element includes code disc 50 and wiper 56, the code branch for the third element includes code disc 51 and wiper 57, and the code branch for the fourth element includes code disc 52 and wiper 58. Upon the connection of a combination of the wipers 55, 56, 57, and 58 to the positive pole of the direct current source for the purpose of setting the endless chain from its normal position to the stopping position to which the particular combination pertains (see the table given earlier), the driving electromotor 9 is energised over one or more of the control circuit code branches. As will be clear from studying the immediately preceding paragraph in conjunction with

the said table, the arrangements are such that until the requisite stopping position is reached there is always at least one of the control circuit code branches effective to maintain an energizing circuit for the driving electromotor and that when the requisite stopping position is reached the condition obtains that none of the four code branches is effective. Thus when the requisite stopping position is reached the endless chain is almost immediately brought to rest by the friction which is normally operative to oppose its movement. Owing to the fact that the driving electromotor drives the endless chain 2 through the medium of a high-ratio reduction gear train, variations (within the limits obtaining) in the number of revolutions due to momentum made by the rotor 27 of the electromotor following upon the opening of the energizing circuit of the electromotor have for practical purposes only a negligible effect upon the accuracy of the setting.

Referring now to Figs. 4 and 5, the changing display indicator to which these figures pertain is one in which a multi-faced indicator structure 61, herein for convenience in description termed the indicator drum, provides the display surfaces. The indicator drum comprises three display slats 62 arranged equiangularly around the axis of the drum, and therefore has an hexagonal appearance in cross-section. Only two of the three display slats are seen in Fig. 4. The indicator drum further comprises three transverse members 63 to which the slats 62 are secured by rivets 64. The indicator drum is directly coupled to the rotor 65 of the code switching device of the indicator and to a gear wheel 71. The assembly comprising the indicator drum 61, rotor 65, and gear wheel 71 is mounted between two end plates 72 and 73 by means of bearing members 74 and 75 carried by and secured to, these end plates. The end plates 72 and 73 are fixed to each other, and held at the requisite distance apart, by three tie members 76 and six nuts 77. Only two of the tie members 76, and four of the nuts 77, are seen in Fig. 4. The nuts 77 are screwed onto studs which pass through holes 78 (see Fig. 5) in the end plates. Fig. 5 shows a side view of the end plate 72 with the driving electromotor, gear train, and code switching device of the indicator in position thereon. The individual driving electromotor 79 of the indicator is coupled to the indicator drum 61 (and to the rotor 65) by a high-ratio reduction gear train comprising pinions 66, 68, and 70 and gear wheels 67, 69, and 71. The figures or letters or numbers or words or other representations on the display surfaces of the display slats 62 will of course be painted or otherwise formed thereon to suit the manner in which the indicator is mounted for use. By way of example, a typical display is shown on the particular display surface that is seen in Fig. 4. The driving electromotor 79 is assembled, as regards the assembling together of its main constituent parts, on the end plate 72. It is similar to the driving electromotor 9 of Figs. 1 and 2, and therefore no description of its construction and operation is necessary.

The rotor 65 of the code switching device of the indicator now being described includes four conducting discs 80, 81, 82 and 83 which are in permanent electrical connection with one another through the medium of three conducting spacers 84. The four conducting discs and the three conducting spacers are suitably clamped together and insulated from the end plates 72 and 73 and indicator drum 61. Disc 80 is a feeder disc, disc 81 is a reset disc, and discs 82 and 83 are code discs. Fixed wipers 85, 86, 87 and 88 are associated with the conducting discs 80, 81, 82, and 83 respectively. The wiper assembly is secured to the end plate 72, the fixed wipers being suitably insulated from one another and from the end plate. Movement of the indicator drum 61, whether for setting it to cause a particular display surface to be displayed or for resetting it to its normal position, is

always in the direction such that the corresponding movement of the rotor 65 is anticlockwise as seen in Fig. 5.

For the purposes of this description, it will be assumed that the display surface which is displayed when the indicator drum 61 is occupying its normal position is a blank, and the display surfaces which are displayed when the drum is at its first and second stopping positions from normal will be termed display surfaces No. 1 and No. 2 respectively. When the indicator is connected in circuit ready for use, the lead 24 (Fig. 3) of the driving electromotor 79 is connected to the negative pole of the direct current source concerned, and the lead 25 (Fig. 3) is connected to wiper 85 of the code switching device of the indicator. To reset the indicator drum to its normal position, the wiper 86 associated with the reset disc 81 is connected (in the external control circuit by which the indicator is being controlled) to the positive pole of the direct current source, the wipers 87 and 88 being of course left disconnected from this pole so far as external connections to them are concerned. To set the indicator drum to display the display surface No. 1 the wiper 87 associated with the code disc 82 is connected (in the external control circuit) to the positive pole of the direct current source, and to set the indicator drum to display the display surface No. 2 the wiper 88 associated with the code disc 83 is connected in this manner the wiper 86 being of course in either case left disconnected from the said positive pole so far as the external connections to the wiper are concerned. Each of the conducting discs 81, 82 and 83 has portions cut away, so that a through circuit between the disc and the associated fixed wiper only exists when the rotor 65 of the code switching device is occupying certain positions or moving between certain positions. The form of the reset disc 81 is such that no through circuit between the disc and its associated wiper 86 exists when the indicator drum 61 is occupying its normal position, but that such a through circuit is closed during the course of movement of the drum from its normal position to its first stopping position (from normal) and thereafter remains closed until the drum again gets back to its normal position whereupon this through circuit is opened. The form of the code disc 82 is such that a through circuit between the disc and its associated wiper 87 exists when the indicator drum 61 is occupying its normal position, and that during movement of the drum from its normal position through the stopping position and back to its normal position this through circuit is opened when the drum reaches its first stopping position (from normal), and is again closed during the course of the movement of the drum from its first to its second stopping position. The form of the code disc 83 is such that a through circuit between the disc and its associated wiper 88 exists when the indicator drum 61 is occupying its normal position, and that during movement of the drum from its normal position through the stopping positions and back to its normal position this through circuit is opened when the drum reaches its second stopping position (from normal), and is again closed during the course of the movement of the drum from its second stopping position to its normal position. The manner of operation of the indicator now being referred to will be apparent from what has just been stated and the description previously given in regard to the indicator illustrated in Figs. 1 and 2.

Electrically-operated changing display indicators according to the present invention may be employed for example as railway station platform indicators.

What I claim is:

1. An electrically-operated changing display indicator arranged for control by multi-element code signals, comprising a driven member having a normal position and a plurality of stopping positions at which different display surfaces are displayed, a control circuit for controlling the setting of said driven member, said control circuit being connected between the two sides of a power

supply circuit and having a main portion and a single resetting branch and for each element of the code employed a code branch, said code and resetting branches all being in parallel with one another, a code switching device, a rotor forming part of said code switching device and coupled to said driven member so as to be driven in correspondence therewith, a conducting code disc forming part of said rotor for each said code branch and a single conducting reset disc forming part of said rotor, all said conducting discs being in permanent electrical connection with one another and together constituting the common point of said main portion and said code and resetting branches of said control circuit, a fixed wiper individual to each said conducting code disc for connecting the corresponding said code branch to said common point and a fixed wiper individual to said conducting reset disc for connecting said resetting branch to said common point, said conducting code and reset discs having portions cut away so that a through circuit between each of these discs and its wiper exists only when said rotor is occupying certain positions and moving between certain positions depending upon the disc, a fixed wiper co-operating with said rotor for continuously connecting said main portion of said control circuit to said common point, means for closing, subject to the switching performed by said code switching device, different combinations, corresponding to different code signals, of said code branches of said control circuit, for bringing about the setting of said driven member from a normal position, means for closing, subject to the switching performed by said code switching device, said resetting branch for bringing about the resetting of said driven member to a normal position, a driving electromotor

individual to the indicator and connected in said main portion of said control circuit and energised, in the setting of said driven member, until said driven member reaches or is about to reach the requisite position, the cutting of said conducting code and reset discs being adapted to this end and friction normally operative to oppose movement of the driven member being relied upon to bring said driven member to rest in the requisite position, and a reduction gear train permanently coupling said driving electromotor to said driven member and having a reduction ratio high enough to ensure that variations, within the limits obtaining, in the number of revolutions due to momentum made by the rotor of said electromotor following upon the open-circuiting of the electromotor have for practical purposes only a negligible effect upon the accuracy of the setting.

2. An electrically-operated changing display indicator as claimed in claim 1 in which said driving electromotor is a direct current electromotor comprising a plurality of field electromagnets, an unwound rotor, and a commutator device driven by said rotor and connecting said field electromagnets in circuit sequentially.
